CLAIM

The ornamental design for an automatic winding watch display box with LCD control panel, as shown and described.

DESCRIPTION

FIG. 1 is a perspective view of an automatic winding watch display box with LCD control panel showing my new design. FIG. 2 is a front view thereof.

FIG. 3 is a rear view thereof.

FIG. 4 is a left end view thereof.

FIG. 5 is a right end view thereof.

FIG. 6 is a top view thereof.

FIG. 7 is a bottom view thereof; and,

FIG. 8 is a perspective view in an open position thereof. The broken lines in the drawings depict unclaimed environmental subject matter.
